(57) **CLAIM**

The ornamental design for a portable information collection and presentation device, as shown and described.

DESCRIPTION

FIG. 1 is an exploded view of the portable information collection and presentation device showing interchangeable right and left end components, taken from a right front top position.

FIG. 2 is an assembled isometric view thereof, taken from a right front top position.

FIG. 3 is an assembled isometric view thereof, taken from a left rear bottom position.

FIG. 4 is a view similar to FIG. 2, showing an assembled view thereof with a left hand end component of FIG. 1 on both right and left ends thereof; and,

FIG. 5 is a view similar to FIG. 3, showing an assembled view thereof with a left hand end component of FIG. 1 on both right and left ends thereof.

The right and left end components of FIG. 1 are interchangeable in positions, or both end components may be of the type shown as the left end component.
